BIROTARY ENGINE

Andre J. Meyer, Lexington, Ky., assignor to
 Mawen Motor Corporation, New York, N. Y.,
 a corporation of Delaware

Application October 18, 1938, Serial No. 235,571

25 Claims. (Cl. 121—59)

The present invention relates to engines and has particular reference to engines of the type in which a bank of radially arranged cylinders is mounted for relative rotary movement with respect to an annular ported valve member encircling the cylinder bank and controlling the flow of gases to and from the cylinders. Engines of this kind may be constructed with the valve member stationary and the cylinder bank rotating or with the valve member and cylinder bank both rotating, but at different speeds, so as to produce relative rotary movement therebetween. In the former case, which is usually the preferred construction, the cylinder bank and crankshaft are both mounted for rotary movement, the relative movement between these parts being governed by gearing connecting the two. In such cases the cylinder bank and crankshaft may rotate in the same or opposite directions. In the case where both cylinder bank and valve member rotate, the crankshaft is ordinarily stationary but this part also may rotate. In all cases, however, at least two of the major components on the engine, one of which includes the valve member and the other the cylinder bank, have relative rotary movement and engines of this kind may therefore conveniently be referred to as birotary engines regardless of the components of the engine which are chosen to have absolute rotation or the relative direction of rotation with respect to each other of the components which have relative rotary movement.

Birotary engines are particularly suited for aircraft propulsion, which requires lower speed of rotation for the propeller drive than the most efficient speed of rotation of the component of the engine from which power usually is taken. Consequently, in engines of this kind, reduction gearing is often required between the power shaft and the component of the engine from which it derives power and this reduction gearing may conveniently be combined with the gearing which connects the crankshaft and cylinder bank to maintain them in properly timed relation.

In engines of all kinds, one of the characteristics of operation is vibration due to variations in the value of the torque reaction of the engine. In automotive types of engines the effect of such vibration has been greatly reduced and in fact substantially eliminated by the use of highly resilient mountings between the engine and the structure in which it is mounted, such mountings being commonly referred to as floating power engine mountings. These mountings are not only resilient but in many instances are so placed with

reference to the center of gravity of the engine that the inertia of the mass of the engine itself assists in neutralizing the vibration due to variation in torque reaction. In radial engines, comparatively little has been done to neutralize vibration due to torque reaction variations, the reason for this being that the problem is exceedingly difficult to solve for this type of engine, due among other things to the fact that in the usual aircraft installation of radial engines no front support is practically obtainable for the stationary part of the engine.

In the birotary engine, particularly in that type of birotary engine in which the cylinder bank and crankshaft rotate in opposite directions, an unusual condition exists from which it has been inferred that the engine is inherently balanced with respect to torque reaction. This, however, can be shown by analysis to be not the case, and a primary object of the present invention is to provide a new and improved construction in birotary engines whereby in a very simple and practical manner vibration due to variations in torque reaction of the engine can be substantially neutralized. A further general object of the invention is to provide a novel and practical arrangement of gearing which will accomplish the desired function of providing properly timed relative rotation between the relatively rotating components of the engine; which is well adapted to be used in combination with means for neutralizing variations in torque reaction and which is also well adapted in addition to its other functions to provide for a gear reduction between the power output shaft of the engine and the power delivering component of the engine from which the power is primarily derived.

Other and more detailed objects of the invention, the manner in which the several objects are achieved, and the advantages to be derived from the use of the invention will best be understood from a consideration of the ensuing portion of this specification, in which is described by way of example a preferred embodiment of construction, taken in conjunction with the accompanying drawings in which:

Fig. 1 is a side elevation of a birotary engine embodying the invention;

Fig. 2 is a front elevation of the engine shown in Fig. 1;

Fig. 3 is a side view, partly in elevation and partly in section and on enlarged scale, of a part of the engine shown in Fig. 1;

Fig. 4 is a section taken on line 4—4 of Fig. 3; and

Fig. 5 is a diagram illustrating the nature of the motions derived from the gearing illustrated in Fig. 3.

Referring now to the drawings, the engine illustrated is of a preferred form of the birotary type in which the valve member is stationary and in which the cylinder bank and crankshaft both rotate but in opposite directions. As will herein-after more clearly appear, however, the invention is not limited in its application to this specific form of birotary engine.

In the engine illustrated, the stationary structure comprises front and rear casing members 10 and 12, respectively, between which the annular ported valve member 14 is fixed. In the embodiment illustrated, the engine is secured to the structure carrying it by means of suitable mounting brackets 16 formed on the rear casing member 12. These parts, which in the present embodiment are all rotationally stationary, may be said to constitute one of the major components of the engine.

Rotatably mounted within the casing structure on suitable bearings 18 and 20 (Fig. 3) is the second major component of the engine consisting of a cylinder bank formed by a plurality of radially arranged cylinders 22 (of which there are seven in the present embodiment) secured to a crank case structure 24 carried by the bearings 18 and 20. While for simplicity of illustration only one cylinder bank has been illustrated, it will be understood that within the scope of the invention the engine may comprise a plurality of cylinder banks mounted in line one behind another.

Each of the cylinders 22 is provided with a suitable piston 24 and the piston of all of the cylinders of the bank are connected through any suitable arrangement of connecting rods, one of which is shown at 26 in Fig. 3, to the crank pin 28 of a crankshaft 30 which may be considered as the third major component of the engine. Crankshaft 30 is mounted in suitable bearings for relative rotation with respect to both the cylinder bank and the stationary structure of the engine.

The several cylinders of the bank are open at their outer ends and have located therein sealing elements 32 of cuff-like form providing cylinder ports 34 through which gases are admitted to and exhausted from the cylinders as the cylinders pass the inlet ports and exhaust ports formed in the valve member. The position of the inlet ports is indicated at 36 on Fig. 2 and that of the exhaust ports at 38 on Figs. 2 and 3. The several ports in the valve member are closed when not in communication with a cylinder port by means of an annular sealing ring 40 carried by the cylinder bank and having suitable apertures therein through which the sealing elements 32 project. The specific form and arrangement of the sealing means between the ends of the cylinders and the valve member and also the combustion cycle of the engine are not material to the present invention and need not be described in detail herein for an understanding of this invention.

Referring now more particularly to Fig. 3, the power output shaft 42 of the engine, which shaft in the present embodiment may be considered as a fourth major component of the engine, is mounted in alignment with the axis of rotation of the crank and is supported for relative rotation with respect to the crankshaft by means of a pilot bearing 44 in the front end of the crankshaft and a bearing 46 carried by a front end

plate 48 bolted to the stationary casing member 10 and forming a part of the stationary structure of the engine. The front end of the crankshaft has keyed or splined thereto an internal gear 50 meshing with a series of planet pinions 52 carried on pins 54 which are in turn carried in a planet carrier 56 of drum-like form, suitably apertured as shown in the lower portion of Fig. 3 to permit the planets 52 to project into meshing contact with the crankshaft gear 50. The planet carrier 56 is fixed to the power shaft 42, advantageously by means of splines 58 on the carrier and on a disc-like flange 60 formed on the shaft. The planets 52 also mesh with a stationary gear 62, the mounting of which will be described more in detail later.

The cylinder bank has fixed thereto a ring gear 64 with internal teeth, which gear is advantageously bolted to the crank case structure by means of bolts 66 which also serve to retain a gear case member 68 which at its forward end is mounted on a bearing 70 to provide a support hereinafter more fully referred to.

Gear 64 meshes with a set of planet pinions 72 forming one part of a set of compound planets, the remaining part of which is formed by a set of planet pinions 74. The compound planets are mounted for rotation on pins 76 which, like the pins 54, are mounted in the planet carrier 56, and the part of the planet carrier in which the compound planets are mounted is provided with suitable apertures through which the planet pinions may project to mesh with their respective gears. The pinions 74 mesh with a ring gear 78 having internal teeth which gear, like the sun gear 62 with which the planets 52 mesh, is stationary.

Gears 78 and 62 are held stationary by suitable key means indicated at 80 between the hub portions of these gears and a stationary sleeve 40 member 82 encircling the power shaft 42 and extending between this shaft and the hub portions of the stationary gears. At its forward end, sleeve 82 is provided with a hub portion 82a, the periphery of which is provided with a series of teeth or splines 84 (see Fig. 4) engaging similar teeth or splines on an annular disc-like torque transmitting member 86 which at its outer periphery is clamped by means of bolts 88 to the stationary casing structure. Member 86 is made of elastic material such, for example, as Bakelite and is preferably designed with respect to its cross-sectional area so that the torque transmitted through the member will result in uniform unit stress therein. Materials other than Bakelite may be used for this member, the primary requisite of which is that the material shall be resilient and elastic in nature and at the same time of sufficient strength to transmit the required forces without distorting to an extent which will allow gears 62 and 78 to turn sufficiently to adversely effect the phase relation between the parts connected.

Advantageously, the hub portion 82a of the sleeve 82 is resiliently clamped between annular friction rings 90 and 92 which may advantageously be of Bakelite, these rings bearing on the opposite side faces of the hub and exerting clamping pressure thereon by virtue of a series of springs 94 carried in suitable sockets in the plate 48 and bearing at their outer ends against the friction ring 92.

Referring now to Figs. 3 and 5, the motion of the several major components of the engine de-

rived from the above described gearing is as follows:

Upon rotation of the crankshaft of the engine, in counter-clockwise direction as viewed in Fig. 5, the crankshaft gear 50, rotating in the direction of the arrow 100 in Fig. 5 causes the planets 52, which mesh with the stationary gear 62, (which for convenience of identification may be referred to as the inner stationary gear and which also is the sun gear of the planetary system including planets 52 and crankshaft gear 50) to rotate about their own axes in the direction of the arrow 102 and also to rotate in a circular path or orbit around the center of the gearing in the direction of the arrow 104. The rotation of planets 52 in their orbital path causes the planet carrier to rotate in the same direction and at the same speed, which speed is less than that of the crankshaft gear 50. Consequently, the power shaft 42 is caused to rotate in the same direction as but at a lower speed than the crankshaft, thus providing a gear reduction between the crankshaft and the power shaft which is desirable for aircraft and other relatively slow speed drives.

Upon rotation of the planet carrier due to the orbital movement of the pinions 52, the pinions 74 meshing with the stationary gear 78 (which may for convenience of identification be termed the outer stationary gear and which also is in effect the sun gear of the planetary system including the compound planets and the cylinder gear 64) are caused to move in an orbital path in the direction indicated by the arrow 106 in Fig. 5, and this orbital movement results in these pinions rotating about their own axes in the direction of the arrow 108. This rotation of pinions 74 about their own axes, combined with the orbital movement imposed by the rotation of the planet carrier, causes the pinions 72, which mesh with the cylinder gear 64, to move in an orbital path indicated by arrow 110 and to rotate about their own axes in the direction indicated by arrow 112. In the present embodiment, pinions 72 are of larger diameter than pinions 74 and since the speeds of these two sets of pinions in their orbital paths and their speed of rotation about their own axes is the same, it will be evident that if the smaller pinion 74 meshes with a stationary gear, as it does, the larger pinion 72 will impose on the gear with which it meshes a rotational movement in the direction of the arrow 114. As viewed in Fig. 5, the assumed direction of rotation of the crankshaft gear 50 is counter-clockwise as indicated by arrow 100 and the direction of rotation imposed by pinion 72 on the cylinder gear 64 is clockwise, as indicated by arrow 114. From a consideration of Fig. 5 it will be apparent that if the relative sizes of pinions 72 and 74 were to be reversed as compared with the relation shown in Figs. 3 and 5, and their respectively meshing gears correspondingly altered in size, the direction of movement of the cylinder gear 64 imposed by the pinions 72 would be the reverse of that shown in Fig. 5 so that this gear would rotate in the same direction as the crankshaft gear. It will be thus evident that the gearing illustrated may be employed with equal facility to different kinds of birotary engines in which the cylinders and crankshaft may rotate in opposite directions or in the same direction.

It is apparent that in any engine torque reaction must be transmitted between parts to which torque is applied in the generation of power or

because of the delivery of power and the part or parts providing a mounting for the engine which parts may be said to provide or constitute a torque reaction absorbing abutment.

In the present engine, the reaction absorbing abutment is constituted by the stationary casing structure which is fixed against rotation and to which the net torque reaction from the power generating and delivering components of the engine must eventually be transmitted.

In the present form of engine, the cylinder bank, constituting one of the engine components, transmits torque reaction due to the side thrust of the pistons on the cylinders. This torque reaction is transmitted in the present instance through the cylinder gear and the planet carrier to the stationary gear 78. The net torque reaction from the power shafts, that is, the crankshaft 30 and the power output shaft 42, is transmitted through the planet carrier to the stationary gear 62. Thus, it will be seen that all torque reaction between the several components of the engine is eventually transmitted through either gear 62 or gear 78 to the sleeve 82. Variations in the value of the net torque reaction will tend to cause this sleeve to vibrate but such vibration is, in accordance with the present invention, substantially absorbed by the resilience of the elastic torque reaction absorbing member 86 interposed between this sleeve member, in which all torque reaction is concentrated, and the stationary torque absorbing abutment provided by the stationary component of the engine.

In connection with this function of the member 86, it is particularly to be noted that one feature of construction in accordance with the present invention permits this member to be loaded in torsion only. As will be observed from Fig. 3, the inner race of the bearing 70 is fixed to an annular disc-like stationary member 86 which at one end bears against the stationary sleeve 82 and at its other end is clamped to the stationary casing structure by the bolts 88. It will thus be seen that the weight of the cylinder bank is supported at the forward end of the engine by what is in effect a bridge construction consisting of the rigid gear case member 68, bearing 70 and member 86, which transmits the weight directly to the stationary casing structure. This evidently relieves the member 86 from the support of any of the engine weight so that the only stress imposed on this member is the torsional stress of the torque transmitted through it.

In any system in which vibrations occur, there is constant interchange of the form of the energy represented by the vibrations, from kinetic to static, and vice versa. This condition we have in the present instance in which the sleeve member 82 tends to vibrate due to variations in the torque reaction transmitted to this member. The energy which is being constantly transformed back and forth between the kinetic and static forms is, in effect, locked in the system and can be dissipated only by some form of damping means which will serve to absorb the energy. Such damping means is provided in the present instance by the friction rings 90 and 92 which serve to dissipate at least a substantial portion of the trapped energy, when it is in kinetic form, into heat. It will be understood, of course, that the amplitude of vibration permitted by the elastic member 86 is relatively very small so that the amount of heat generated by friction due to oscillation of the sleeve 82 relative to the stationary

casing structure is sufficiently small to be readily dissipated by radiation without producing overheating of the parts.

From the foregoing it will be evident that many variations in the specific design of apparatus employed may be made without departing from the scope of the invention, the principles of which may be applied, as hereinbefore indicated to many different kinds or types of birotary engines, and some features of which may be employed to the exclusion of others. The invention is accordingly to be understood as embracing all forms of structure falling within the scope of the appended claims.

15. What is claimed is:

1. A birotary engine comprising a plurality of major engine components having relative rotary movement with respect to each other and including a component fixed against rotation and constituting the component by which the engine is mounted, and means for maintaining the relatively moving components in desired phase relation including an elastic connection in the path of torque transmission between the mounting component and the remainder of said components.

2. A birotary engine comprising a plurality of major engine components mounted for relative rotary movement with respect to each other and including a component fixed against rotation and constituting the component by which the engine is mounted, and means including gearing for maintaining the relatively moving components in desired phase relation, said means further including an elastic connection in the path of torque transmission between the mounting component and the remainder of said components.

3. In a birotary engine, a plurality of major engine components having relative rotary movement with respect to each other, an engine component providing means for mounting the engine, gearing interconnecting said relatively rotating components, and elastic means for resiliently transmitting from said gearing to the mounting component the torque reaction from said relatively rotating components.

4. In a birotary engine, stationary casing structure including a valve member, a cylinder bank mounted for rotation relative to said valve member, a crankshaft mounted for rotation relative to said valve member and said cylinder bank, and means including an elastic member for transmitting torque reaction from the rotating components to said casing structure.

5. In a birotary engine, stationary casing structure including a valve member, a cylinder bank mounted for rotation relative to said valve member, a crank shaft mounted for rotation relative to said valve member and said cylinder bank, gearing connecting said cylinder bank and said crankshaft including a part required to be held rotationally stationary relative to said casing structure and to which torque reaction from the rotating components is transmitted, and an elastic member for connecting said part to said casing structure.

6. In a birotary engine, a plurality of major engine components having relative rotary movement with respect to each other including a rotationally stationary component providing means for mounting the engine, planetary gearing interconnecting said relatively rotating components, said gearing including a gear required to be held rotationally stationary relative to the mounting

component, and elastic means for connecting said gear to the mounting component.

7. In a birotary engine, engine components comprising a cylinder bank, a crankshaft, a power output shaft and a casing structure including a valve member, said components being mounted for relative rotary movement with respect to each other and one of said components being rotationally stationary to provide means for mounting the engine, and means including gearing for maintaining the desired phase relation between the several components, said means including an elastic connection in the path of torque transmission between the mounting component and each of the remainder of said components.

8. In a birotary engine, a cylinder bank and a crankshaft mounted for relative rotary movement, with respect to each other, gears on said members, stationary gears, a planet carrier carrying a plurality of sets of planets for connecting each of the first mentioned gears with a stationary gear, stationary engine mounting structure including a valve member cooperating with the cylinders, and an elastic connection between said stationary structure and said stationary gears.

9. In a birotary engine, a cylinder bank and a crankshaft mounted for relative rotary movement with respect to each other, gears on said members, a plurality of stationary gears, a planet carrier carrying a plurality of sets of planets for connecting each of the first mentioned gears respectively with a different one of said stationary gears, and a power output shaft driven by said planet carrier.

10. In a birotary engine, a cylinder bank and a crankshaft mounted for relative rotary movement with respect to each other, gears on said members, stationary mounting structure, stationary gears, a planet carrier carrying a plurality of sets of planets for connecting each of the first mentioned gears with a stationary gear, a power output shaft driven by said planet carrier, and an elastic connection for connecting said stationary gears to said mounting structure.

11. In a birotary engine, a rotatable cylinder bank, a rotatable crankshaft, a power output shaft, a first planetary gearing including a first stationary gear providing a gear reduction for driving the power output shaft at reduced speed relative to crankshaft speed, and a second planetary gearing associated with said first gearing and including a second stationary gear providing a gear connection between the crankshaft and the cylinder bank.

12. In a birotary engine, a rotatable cylinder bank, a rotatable crankshaft, and gearing for maintaining the cylinder bank and crankshaft in desired phase relation, said gearing comprising two interconnected planetary gear systems each including a stationary gear and said systems having a common planet carrier and one of said gear systems including compound planets.

13. In a birotary engine, a rotatable cylinder bank, a rotatable crankshaft, gearing for maintaining the cylinder bank and crankshaft in desired phase relation, said gearing comprising two interconnected planetary gear systems having a common planet carrier, each of said systems including a stationary gear, and elastic means for connecting said stationary gears to a rotatably stationary part to prevent their rotation and to absorb variations in torque reaction transmitted to said stationary gears.

14. In a birotary engine, a rotatable cylinder bank, a rotatable crankshaft, a first planetary

gearing including a crankshaft gear, a stationary gear and a planet carrier carrying planets meshing with said gears, and a second planetary gearing including a second stationary gear, a cylinder gear and compound planets connecting the cylinder gear with said second stationary gear, said compound planets being carried by said planet carrier.

15. In a birotary engine, a plurality of rotatably mounted engine components including a cylinder bank and a crankshaft, a crankshaft gear forming the ring gear of a planetary gearing, a stationary gear forming the sun gear of said gearing, a planet carrier carrying a set of planets meshing with said gears, a cylinder gear forming the ring gear of a second planetary gearing, a second stationary gear, and a set of compound planets carried by said planet carrier each of said compound planets comprising two pinions of different size one of which meshes with said cylinder gear and the other of which meshes with said second stationary gear.

16. In a birotary engine, a plurality of rotatably mounted engine components including a cylinder bank and a crankshaft, a crankshaft gear forming the ring gear of a planetary gearing, a stationary gear forming the sun gear of said gearing, a planet carrier carrying a set of planets meshing with said gears, a cylinder gear forming the ring gear of a second planetary gearing, a second stationary gear, and a set of compound planets carried by said planet carrier each of said compound planets comprising two pinions of different size, the larger of which meshes with the cylinder gear and the smaller of which meshes with the second stationary gear.

17. A birotary engine comprising a plurality of major engine components mounted for relative rotary movement with respect to each other, one of said components fixed against rotation and constituting the component by which the engine is mounted, means including gearing for timing the relative rotary movement between the several components, said gearing including a member required to be held stationary, an elastic connection between said member and said stationary component, and means carried by said stationary component and frictionally engaging said member to damp vibration thereof caused by variations in the torque reaction transmitted thereto.

18. In a birotary engine, a stationary engine component, a plurality of engine components adapted to rotate relative to each other and relative to said stationary component, bearings for transmitting the weight of the rotatable components to the stationary component, and means including gearing for maintaining said components in desired phase relation relative to each other, said means including an elastic member interposed in the path of torque transmission between said stationary component and the rotatable components and said member being free of the weight of any of said components.

19. In a birotary engine having a cylinder bank, a crankshaft and stationary structure for mounting the engine, a crankshaft ring gear, a sun gear, an elastic connection between said sun gear and said stationary structure, a planet carrier carrying a set of planets meshing with said gears, and a power output shaft connected to said planet carrier.

20. In a birotary engine having a cylinder bank, a crankshaft and stationary structure for mounting the engine, a power output shaft in alignment with the axis of the crankshaft, a

crankshaft ring gear, a planet carrier carrying a set of planets meshing with said gear, an annular gear around said power output shaft and meshing with said planets, a driving connection between said planet carrier and said power output shaft, and an elastic connection between said annular gear and said stationary structure.

21. In a birotary engine, a front casing structure, a disk-like elastic torque transmitting member fixed to the forward part of said structure, a sleeve member secured to said torque transmitting member and extending rearwardly therefrom coaxially of the axis of the engine, a crankshaft, a cylinder bank, and gearing including gears on said sleeve member for causing said crankshaft and said cylinder bank to rotate in predetermined phase relation with respect to each other and to said casing structure.

22. In a birotary engine, a front casing structure, a disk-like elastic torque transmitting member fixed to the forward part of said structure, a sleeve member secured to said torque transmitting member and extending rearwardly therefrom coaxially of the axis of the engine, a crankshaft, a cylinder bank, gearing including gears on said sleeve member for causing said crankshaft and said cylinder bank to rotate in predetermined phase relation with respect to each other and to said casing structure, a power output shaft extending through said sleeve member, and a connection between said power output shaft and said gearing for driving the power output shaft at a speed lower than that of the crankshaft.

23. In a birotary engine, a stationary mounting structure, a rotatable cylinder bank, a rotatable crankshaft, gearing connecting said crankshaft and said cylinder bank for maintaining the cylinder bank and crankshaft in desired phase relation with respect to each other, said gearing including a part required to be held stationary, and a disk-like member of elastic material providing a torque transmitting connection between said stationary structure and said part required to be held stationary, said member having different thicknesses at different distances from its center to provide uniform unit stress in the member due to torque transmission therethrough.

24. In a birotary engine, a stationary mounting structure, a rotatable cylinder bank, a rotatable crankshaft, gearing connecting said crankshaft and said cylinder bank for maintaining the cylinder bank and crankshaft in desired phase relation with respect to each other, said gearing including a part required to be held stationary, a disk-like member of elastic material providing a torque transmitting connection between said stationary structure and said part required to be held stationary, means for frictionally contacting the side faces of said disk-like member, and springs for resiliently maintaining said means in pressure contact with said faces.

25. In a birotary engine, stationary housing structure, a rotatably mounted cylinder bank, a rotatably mounted crankshaft, a rotatably mounted power output shaft in alignment with the axis of rotation of the crankshaft, a crankshaft gear, a first stationary gear, a planet carrier carrying a set of planets meshing with said gears, means for connecting the planet carrier to said power output shaft, a cylinder gear, a second stationary gear, a set of compound planets carried by said planet carrier, the pinions of said compound planets being of different size, a sleeve member around said power output shaft, said

stationary gears being fixed to said sleeve member, a torque transmitting member of elastic material for connecting one end of said sleeve member to said stationary structure, and parts including a bearing providing a connection between said cylinder bank and said stationary

structure for carrying the weight of the cylinder bank independently of said gearing, whereby to subject said elastic member to torsional stress only.

ANDRE J. MEYER.
